CLAIM

The ornamental design for a combination snap hook and knife, substantially as shown and described.

DESCRIPTION

FIG. 1 is a front view of the combination snap hook and knife, with the knife shown in closed position.

FIG. 2 is a side view of the combination snap hook and knife, showing the knife side, as shown in FIG. 1.

FIG. 3 is a side view of the combination snap hook and knife, showing the snap hook side, as shown in FIG. 1.

FIG. 4 is an end view of the combination snap hook and knife, as shown from the knife opening end, in FIG. 1.

FIG. 5 is an opposite end view of the combination snap hook and knife, as shown from the pivot end in FIG. 1; and,

FIG. 6 is a front view of the combination snap hook and knife, as shown with the knife rotated into an open position.
